[57] CLAIM

The ornamental design for an expandable oxygen tank bracket for a wheelchair, as shown and described.

DESCRIPTION

FIG. 1 is a perspective view of the expandable oxygen tank bracket for a wheelchair;

FIG. 2 is a front view of the oxygen tank bracket, partially cut-away, showing the oxygen tank in place in dashed lines;

FIG. 3 is a side view of the oxygen tank bracket; and,
FIG. 4 is a perspective view showing the oxygen tank bracket in place and showing the oxygen tank in dotted lines.
